CLAIM

The ornamental design for a dimpled tumbler, as shown and described.

DESCRIPTION

FIG. 1 shows a perspective view of the front and top of the dimpled tumbler of this invention;

FIG. 2 shows a frontal perspective view of the bottom looking upwardly from the bottom of the tumbler;

FIG. 3 shows the back of the tumbler opposite from that shown in FIG. 1; and,

FIG. 4 shows a plan view downwardly from the top of the tumbler.
